Attorney.

UNITED STATES PATENT OFFICE.

EDWARD J. BROOKS, OF EAST ORANGE, NEW JERSEY, ASSIGNOR TO THE
E. J. BROOKS & COMPANY, OF NEW YORK, N. Y.

SEAL.

SPECIFICATION forming part of Letters Patent No. 481,892, dated August 30, 1892.

Application filed May 25, 1892. Serial No. 434,365. (No model.)

To all whom it may concern:

Be it known that I, EDWARD J. BROOKS, a citizen of the United States, and a resident of East Orange, in the State of New Jersey, have 5 invented a new and useful Improvement in Seals, of which the following is a specification.

This invention as a whole consists in an improved seal of that class in which the ends of a flexible shackle are united to fasten the 10 seal by inclosing them or portions of them in a suitable seal-disk or the seal proper and compressing and solidifying such seal-disk or seal proper in a suitable press.

The primary object of the invention is to 15 adapt the seal in a peculiar manner to a new use to which seals have recently been applied—viz., the marking of meat which has been officially inspected in such a way as to prevent the fraudulent use of similar marking 20 devices.

Another object of the invention is to prevent the injury of the hands or persons of those who handle the meat by a spear-shaped extremity with which the shackle of the seal 25 is provided to facilitate thrusting it through the meat.

A sheet of drawings accompanies this specification as part thereof.

Figures I and II of these drawings are 30 respectively a face view and a cross-section of my "spear-seal" for meat, showing it open. Figs. III and IV are like views of the same ready for the press. Figs. V and VI are like 35 views of the pressed seal. Fig. VII is a face view of a modified seal; and Fig. VIII is a magnified view of a piece of shackle-wire, illustrating the preferred method of making the shackle of said seal, Figs. I to VI.

Like reference letters and numbers indicate 40 corresponding parts in the several figures.

Each of the improved seals is composed of a flexible shackle A, preferably of suitable wire, and a compressible seal-disk or seal proper B, which is preferably fast upon one 45 end 10 of the shackle and constructed with a recess 11 in its face, which receives the other end 12 of the shackle, hereinafter termed its "spear" end, flatwise. The shackle A is preferably of iron wire of a suitable gage, tinned, 50 as represented at 13, Fig. VIII, and is provided with a sharp-pointed or spear-shaped

extremity 14 to facilitate thrusting it through the meat (represented at C, Figs. III and V) and with an anchoring device 15 for this shackle end, which does not interfere with so 55 thrusting it through the meat. Said anchoring device 15 is composed of a short re-entrant bend with straight portions of the wire in line with each other on both sides thereof. It is preferably produced, together with a suitable anchoring-bend 16 for the fast end of the shackle and with a suitable sharp-pointed extremity or spear 14, in the manner illustrated by Fig. VIII—that is to say, by rolling the wire with bends 15 16, separated by a short 60 straight portion 14, suitable for the spear, and cutting the wire obliquely, as at 17, Fig. VIII, to sharpen the spear end. The straight portion 18, Fig. VIII, between such a pair of bends and the next pair is sufficient for the 65 required length of shackle and is determined by the circumference of the die-roll. A reciprocating bending-die may be used alternatively to convert the tinned wire into the peculiarly-constructed shackles. The seal- 70 disks B of said spear-seals preferably have their said face-recesses 11 conformed to said anchoring-bends 15, so as to resist the withdrawal of the shackle lengthwise, and formed with closed ends 19, so as to inclose and shield 75 or mask the spear-shaped extremity 14 of the fastened shackle, as in Fig. III. The seal-disks of all the seals may be of any preferred circumferential shape, as illustrated by a dotted circle at B², Fig. VII, and may be of lead 80 or any other compressible material which is adapted to be pressed cold and to retain its shape and lettering, so as to insure the detection of any tampering with the pressed seal. They are also in common adapted to 85 have both shackle ends and their laterally-projecting anchoring devices located in one and the same plane parallel to the face of the disk by the location of said face-recess 11 and the portion 20, which incloses the fast end 10 90 side by side, whereby in the pressed seal, Figs. V and VI, the seal-disk may be very thin, and thus protected against being successfully tampered with. Instead of the said anchoring-bend 16, the fast end 10 may have a bent-up 95 enlargement 21, as in Fig. VII, or any approved anchoring device, and other like modi- 100

fications will suggest themselves to those skilled in the art.

Having thus described the said improvement in seals, I claim as my invention and 5 desire to patent under this specification—

1. A seal for meat, composed of a flexible shackle of wire and a compressible seal-disk to unite the ends of said shackle, the shackle having a spear end which is constructed with 10 a sharp-pointed extremity and with an anchoring device in the form of a short re-entrant bend adapted to be thrust through the meat, substantially as hereinbefore specified.
2. In combination with a flexible shackle

of wire having a spear end comprising a 15 sharp-pointed extremity and an anchoring device in the form of a short re-entrant bend, a compressible seal-disk fast on the other end of the shackle and having a recess in its face conformed to and which admits said spear 20 end and closed at one end to mask said sharp-pointed extremity, substantially as hereinbefore specified.

EDWARD J. BROOKS.
